G. BAKER

AUTOMATIC FUEL OIL SUPERHEATER

Filed May 24, 1927

INVENTOR
GEORGE BAKER

BY *Thurman & Co.*

ATTORNEYS

UNITED STATES PATENT OFFICE.

GEORGE BAKER, OF SEATTLE, WASHINGTON.

AUTOMATIC FUEL-OIL SUPERHEATER.

Application filed May 24, 1927. Serial No. 193,877.

The present invention relates to improvements in an automatic fuel oil super-heater, and its particular object is to provide automatically operating means for pre-heating fuel to be used in a furnace for the purpose of heating water and generating steam, my invention particularly applying to hot water and steam heating systems. A further object of the invention is to utilize the hot water and steam of the system for pre-heating the fuel oil, either singly or in combination. A further object of the invention is to provide means whereby the hot water is kept circulating around a fuel conduit for pre-heating the fuel a long time after the furnace itself has been disconnected from the fuel supply.

Further objects and advantages of my invention will appear as the specification proceeds.

The preferred form of my invention is illustrated in the accompanying drawing which shows diagrammatically the entire system in side elevation.

While I have shown only the preferred form of the invention, I wish to have it understood that various changes or modifications may be made within the scope of the claims hereto attached without departing from the spirit of the invention.

Referring to the drawing in detail, it will be seen that fuel oil is supplied to the furnace 1 from a fuel oil reservoir 2 through the pipe 3, a pipe 4 being provided for returning fuel not used. The furnace is suitably constructed for heating water and for generating steam, and the steam is guided to a heating system through the pipe 6 and is returned from the heating system through the pipe 7. The heating system itself is not shown in the drawing. The hot water is conducted to a storage tank (not shown) through the pipe 8 and returned from the storage tank through the pipe 9.

The pipe 3 presents a horizontal section 11 which passes through a cylindrical retort 12, suitable unions 13 being provided for facilitating the assembly and packing means 14 for rendering the fit steam and water-tight. Hot water is taken from the pipe 8 and is conducted through a pipe 16 to one

end of the retort 12 while the other end of the retort 12 is connected through a pipe 17 with the furnace, so that water may freely circulate through the retort and return to the boiler in the furnace. A valve 18 controls the pipe 16 and a valve 19 controls the pipe 17.

The pipe 7, being the return steam pipe, is connected through a pipe 21 to the retort 12 and includes an expansion chamber 22 rising vertically from the retort. The expansion chamber is provided with an automatic air relief valve 23 at the end of a pipe 24 connected to the lower end of the expansion chamber. A valve 26 controls the pipe 21. A suitable drain cock 27 is provided at the bottom of the retort 12 and a thermometer 28 allows the temperature within the retort to be established.

In using my system it is apparent that the oil before it reaches the furnace is pre-heated by passing through the retort 12. Water passes from the pipe 8 through the pipe 16 and the retort, for pre-heating the oil flowing through the pipe 11, and the water returns through the pipe 17. Steam is conducted through the pipe 21 and the expansion chamber 22 into the retort and also returns through the pipe 17. When the steam enters the expansion chamber 22 it first drives the air out of the said chamber through the relief valve 23. When the fuel supply is turned off, generation of steam is discontinued and the steam in the chamber 22 condenses and creates a vacuum which draws on the heated water in the retort 12 and causes the retort to ebb back and forth for a number of hours after the furnace has been disconnected. The arrangement of the valves allows either steam or water to be used singly for pre-heating the oil or in combination.

I claim:

1. In combination, a furnace for heating water and generating steam, a pipe for feeding fuel oil to the furnace, means for guiding heated water and the steam independently around a section of the pipe and individual control means for the water and the steam, an expansion chamber in the steam-conducting means and adapted to be evacu-

ated thereby for producing a vacuum when the steam condenses and for causing the water to pulsate back and forth.

2. In combination, a furnace for heating water and generating steam, a pipe for feeding fuel oil to the furnace, a retort surrounding said pipe, means for conducting hot

water through the retort, independent means for conducting steam through the retort including an expansion chamber rising from 10 the retort and independent control means for the water and steam conducting means.

GEORGE BAKER.
